UNITED STATES PATENT OFFICE.

GEORGE E. WALKER, OF PRESTWICH, SAMUEL H. WALKER, OF SOUTHPORT, AND FRANK HEWITT, OF RADCLIFFE, ENGLAND.

MACHINE FOR THE PRODUCTION OF METAL TAGS SUCH AS USED ON LACES.

1,395,536.

Specification of Letters Patent.

Patented Nov. 1, 1921.

Application filed February 9, 1920. Serial No. 357,407.

To whom it may concern:

Be it known that we, GEORGE EDWARD WALKER, SAMUEL HERBERT WALKER, and FRANK HEWITT, British subjects, residing at 5 Prestwich, county of Lancaster, England, Southport, county of Lancaster, England, and Radcliffe, county of Lancaster, England, respectively, have invented certain new and useful Improvements in Machines 10 for the Production of Metal Tags Such as Used on Laces, of which the following is a specification.

This invention relates to improvements in machines for the production of metal tags 15 such as used on laces or other articles.

Such tags have hitherto been manufactured by a series of operations each carried out on a separate machine, and the object of 20 the present invention is a machine in which all the operations for the production of the tag can be carried out.

It consists of a machine constructed with 25 a chute through which a sheet of thin metal or other material is fed, a fixed die or former for shaping the tag as the strip is cut off, a reciprocating punch and cutter to shear off the desired length of metal and force it into the forming die, and a row of 30 punches or needles reciprocating in the opposite direction to perforate the tag and give it a serrated or roughened internal surface.

The invention will be fully described with 35 reference to the accompanying drawings.

Figure 1 is a longitudinal section of the machine.

Fig. 2 is a plan.

Fig. 3 is a detached sectional elevation of 40 the die former A, reciprocating punch B, and needle punches C in position before operation.

Fig. 4 is a plan of same.

Fig. 5 is a detached sectional elevation of 45 the die former A, the reciprocating punch B, shearing tool D and needle punches C in position during the operation of forming the tag.

Fig. 6 is a plan of same.

The machine is constructed with a bed or 50 frame A' of suitable design to which is rigidly attached a die former A. To one side of the die former A is mounted a reciprocating bar B' sliding in suitable guides and to the other side of the die former A a second reciprocating bar C'.

To the free end of the reciprocating bar B' a cutting or shearing tool D, a reciprocating punch B and a measuring or distance plate b are fitted to move to and from the die former A with the bar, and to the free 60 end of the reciprocating bar C' a series of needle punches C are fitted to move to and fro with it. Holes are formed in the die former A and in the punch B to receive the needle punches C. Instead of needle punches, a tool to indent the tag may be employed. 65

Above the die A and punch B a magazine or chute E is mounted to deliver the tag material to the machine. The chute E is preferably suspended from a pivot at e on an arm or bracket e' to permit it to swing to and fro with the punch and at its lower end is carried in a sliding guide piece F being drawn back to normal position by a spring f. 70

The reciprocating bar B' and with it the punch B and shearing tool D is moved in one direction by a cam G or by an eccentric crank or other means on a driving shaft g and in the opposite direction by the spring 80 g', and the reciprocating bar C' is connected to the bar B' by a connecting rod H and lever h to cause it to move simultaneously but in the opposite direction so that as they move the punch B and needle punches C approach and recede from one another. 85

In operation a thin strip of metal or other material is fed from the chute E on to the measuring plate b preferably falling by gravity. On the forward movement of 90 the bars B' and C' the shearing tool D cuts off the length of metal to form the tag and the punch B forces it into the interior of the die former A giving it a U shape. While still held by the die former A and 95 the punch B the needle punches C enter from the other side and form a number of holes in the tag, forming a rough surface in the interior. When the punches recede the finished tag falls out through the bottom of the die former A. 100

The die former may be of any suitable shape for any particular form or shape of tag.

What we claim as our invention and desire to protect by Letters Patent is:— 105

A tag forming machine constructed with a fixed or stationary die former, a reciprocating bar carrying a cutting tool and punch at one side of the die former, a reciprocating 110

ing bar carrying needle punches at the other side of the die former, the two bars being connected to move simultaneously in opposite directions to approach and recede from one another, and an oscillating chute to deliver the tag material in front of the die former, means to suspend the chute and means to cause it to swing to and fro with the punch substantially as described.

In testimony whereof we have hereunto 10 set our hands in presence of two subscribing witnesses.

GEORGE E. WALKER.
S. H. WALKER.
FRANK HEWITT.
